UNITED STATES PATENT OFFICE.

JOHN SUTINEN, OF TWO HARBORS, MINNESOTA.

RAILROAD TIE.

Application filed February 23, 1928. Serial No. 256,183.

This invention relates to railroad ties and has special reference to improvements upon the type of tie patented to me November 29th, 1927, No. 1,651,106, the principal object being 5 to provide a more practical and efficient tie of this type and attachments therefor.

Other objects and advantages of the invention will appear in the further description thereof.

10 Referring now to the accompanying drawing, forming part of this application, and wherein like reference characters indicate like parts:

Figure 1 is a top plan view of one of my 15 improved ties and rail mountings therefor, one of the latter being complete and the other incomplete;

Figure 2 is an elevation of the tie with rails mounted thereupon;

20 Figure 3 is a perspective view of the body portion of the tie proper;

Figure 4 is an elevation of the preferred form of tie assembly at a rail joint;

Figure 5 is a perspective view of one of the 25 mounting members for the tie;

Figure 6 is a similar view of the rail engaging saddles of the tie;

Figure 7 is a plan view of the improved 30 form of anti-spreading device cooperatively connected with the tie; and

Figure 8 is a similar view of the anti-spreading holding means.

1 represents the tie body which I prefer to make of T-iron construction with the web 2 35 thereof in upright position when in use, though it is obvious that a plane angle such as used in my before mentioned patent may be employed if preferred.

40 As a practical and simple mounting for the rail adjacent each end of the tie I provide the channel shaped housing member 3 for bolting directly to one side of the web 2 of the tie body, and this channel is preferably the full depth of the web of the tie and designed to hold tightly against the web a suitable wooden or other like yieldable block 4 45 the ends of said channel being spaced from the web of the tie for such purpose; the manner of fastening said housing 3 differing from my former patent in that holes are provided indicated at 5 directly therethrough so that the bolts for attaching same to the web of a tie are made to pass directly through not only the body portion of the housing but the wood 55 or other cushioning member held between it

and the tie web thus providing a much more simple and efficient form of housing than in my former patent. The block 4 I prefer to provide with properly spaced and sized vertical through holes as indicated at 6 for the reception of the rail holding spikes indicated 60 at 7. On top of this assembly, directly beneath the rail, is placed the U-shaped saddle member 8, it being provided with suitable holes indicated at 9 for the reception of the spikes. There are also formed in the base of the tie body holes indicated at 10 which are 65 equally spaced and like the holes 9 in the saddle 8, and one novel and advantageous feature of my present construction is that the spikes 70 7 are sufficiently long to extend wholly through the base of the tie body, as clearly seen in Figure 2 of the drawings.

Intermediate of each extreme end of the tie and the saddle installation for the rail is 75 formed in the upper edge of the web thereof a downwardly and inclined notch 11 for the reception of the wishbone rail anti-spreading member 12, the apex of which is slightly flattened as at 13 for convenient engagement 80 within said notch. The length of the legs of this wishbone member are such as to reach the rail under normally spread conditions of the members and one of said legs is provided with an upset bulge or tit as indicated at 14 so as 85 to prevent slipping of the holding hook bolt 15 by which adjustment of the wishbone is accomplished. This hook bolt carries a hook washer 16 which is impinged by the nut 17 on the bolt and it is obvious that when this 90 adjusting bolt is hooked over the two diverging legs of the wishbone and the nut drawn up it will draw the extreme ends of the anti-spreading member together and tend to increase the distance between the notch 11 in the 95 tie and the top of the rail, thus adequately acting as a secure anti-rail spreading member which as is understood by those conversant with the art are ordinarily used only at curves or the like but I prefer to equip all of the 100 ties with cooperative means for the utilization of such.

In the use of my invention at the union of two rails such as shown in Figure 4 I have shown two spaced tie bodies of the angle bar 105 construction as at 18, they being placed back to back and each equipped with a housing member 3 and block 4 through which the rail spikes extend, and intermediate of the rail bases and the tie assembly I have shown a 110

single elongated saddle member 19 which overlaps both tie assemblies, thus making them as a single supporting member under the joint of the rails, and if desired an additional plate as indicated at 20 may be employed under the angles 18 which results in an exceptionally sturdy and unyielding support for a rail joint, as is obvious.

From the foregoing it is apparent that I
10 have simplified and improved materially my
former construction, and provided an apparently practical railroad tie member.

Having thus described my invention, what

I claim and desire to secure by Letters Patent, is:

15 A railroad tie comprising a body member having an upright portion, a housing member adjacent each end of the tie and bolted in spaced relation to said upright portion, a wooden block within each housing, and an 20 overlapping rail supporting saddle member overlapping the upright portion, block and housing for the purpose described.

In testimony whereof I affix my signature.

JOHN SUTINEN.
